(57) **CLAIM**

The ornamental design for a vehicle grille, as shown and described.

DESCRIPTION

FIG. 1 is a front elevational view of a vehicle grille showing our new design;

FIG. 2 is a front and side perspective view thereof; and,
FIG. 3 is a side cross sectional view taken along line 3-3 in FIG. 1.

The broken line showings of the center marquee, and the areas surrounding the grille are for illustrative purposes only and form no part of the claimed design.
